Patented Sept. 21, 1915.

UNITED STATES PATENT OFFICE.

ORVILLE VIRDEN, OF ST. LOUIS, MISSOURI.

UNDERFEED FIRING DEVICE.

1,153,979.

Specification of Letters Patent. Patented Sept. 21, 1915.

Application filed April 11, 1913. Serial No. 760,541.

To all whom it may concern:

Be it known that I, ORVILLE VIRDEN, a citizen of the United States, and resident of St. Louis, Missouri, have invented certain 5 new and useful Improvements in Underfeed Firing Devices, of which the following is a specification containing a full, clear, and exact description, reference being had to the accompanying drawings, forming a part 10 hereof.

My invention relates to an improved under-feed firing device for steam boiler furnaces, stoves, and other coal-burning apparatus which employ a fire box and grate, 15 and my invention consists in the novel construction hereinafter described and specifically designated in the appended claim.

The object of my invention is to provide an improved under-feed firing device, which 20 shall feed the fuel continuously upward through an opening in the fire grate, whereby it will be unnecessary to open the fire door for the purpose of feeding the fuel to the fire-box and smoke and gases will be 25 consumed, necessarily effecting a marked increase in economy.

In the drawings: Figure 1 is a sectional front elevation of a steam heater or boiler furnace having my invention applied thereto; Fig. 2 is a sectional plan view of the 30 same, the section being taken on the line 2—2 of Fig. 1; and Fig. 3 is a detailed vertical section of a portion of the fire-grate supporting frame.

35 The numeral 1 indicates the usual steam boiler or heater, or it may be a stove, having the usual combustion chamber and fire door 2. The heater 1 is supported upon a cast iron base 3, in which is formed the usual 40 ash pit 4, and which is provided near its upper end with a fixed fire-grate frame 5, inclosing a rectangular space 6, in which are located the rotary and rocking grate bars 7. The said grate-bars 7 are preferably 45 triangular in cross section and provided at their opposite ends with journals 8 mounted in bearings 9. Said bearings 9 are provided on their under side with detachable inverted caps 10, which are held in place by 50 common set screws 11, so that the said journals may be removed from said bearings whenever required (see Fig. 3). The grate-bars 7 are provided with journals 8 and bearings 9 on each end, and the journals on 55 each end are all geared together by means

of common gear wheels or pinions 12 fixed upon said journals. One of said journals 8 projects a distance in front of its front gear wheel 12, and is provided with an angular portion 13 which is to be engaged by the 60 usual shaking-handle or bar or socket crank for the purpose of rotating and rocking all of said grate bars simultaneously in cleaning the fire. Some of said grate bars 7 extend completely across the rectangular space 65 6 of the said grate-bar frame 5, but others of said grate bars are shorter and have the journals on their inner ends mounted on suitable bearings formed in the rectangular feed tube frame and dead-plate 14. Said 70 feed tube frame 14 is smooth and flat on its upper surface and provided with a central feed aperture 15, through which projects the upper end of a curved feed tube 16, which passes downwardly and outwardly through 75 the side of the ash pit 4 and extends a distance in a horizontal direction upon the exterior of said ash pit. The projecting horizontal portion of said feed tube 16 is preferably circular in cross section, and the outer end 80 of the same is closed by a head 17 carrying a bearing 18. Mounted in said bearing 18 is a conveyer shaft 19, the outer end 20 of which is made angular in cross section to receive a hand-crank or socket-wrench 21. Fixed 85 upon said conveyer-shaft 19 in the usual manner, within said feed tube, is a spiral screw conveyer 22. Mounted upon the feed tube exterior of the ash pit is a fuel hopper 23, provided with a hinged cover 24. Fuel 90 from the feed hopper 23 passes downwardly to an opening 25 formed in the said feed tube. The numeral 26 indicates a brace, connected at one end to the said feed tube, and at its opposite end to the ash pit wall within 95 said ash pit, for the purpose of supporting and bracing the curved portion of the said feed tube.

The operation is as follows: Fuel being supplied to the hopper 23 passes downwardly therefrom through the said opening 25 into the conveyer 22, whence it will be forced continuously as long as said conveyer is rotated, by means of the hand crank 21. The rotation of said conveyer 22 forces 100 the fuel through the curved inner portion of said feed tube 16 upwardly through the opening in the combined dead-plate and feed tube frame 14 centrally and above the fire grate, where the said fuel will be par- 110

tially coked on said dead-plate and then burned completely in the usual manner, and smoke will be prevented.

The under-feed method of coal burning 5 brings the fire in direct contact with the most effective heating surfaces of the boiler or stove. The fuel thus discharged into the fire box or fire pot cannot slip back from the grate into the feed tube.

10 The hand crank 21 may be caused to engage the angular portion 13 of the fire grate when it is desired to clean the fire, or a separate shaker handle or wrench may be employed. In some cases I may replace the 15 hand crank 21 by a common gear wheel, worm wheel or sprocket wheel, and continuously drive the conveyer, by means of a steam engine or electric motor, thus feeding the fuel in an uninterrupted stream upwardly through the opening in the fire grate.

I claim:

The improved underfeed firing device for furnaces, the same being composed of a fixed fire-grate and frame having a rectangular

opening therein, a series of long and shorter 25 grate-bars mounted to rotate within said rectangular opening, there being a smaller rectangular opening thus left centrally of the said first-mentioned rectangular opening; a rectangular flat, smooth dead-plate 30 and feed-tube frame fixed within said central smaller rectangular opening, and having bearings in which the inner ends of the said shorter grate-bars are journaled, and also having a central feed-tube opening 35 which is surrounded by the said rectangular dead-plate; a feed-tube connected to said feed-tube opening and extending downwardly and outwardly through the furnace ash-pit; and means for forcing fuel inwardly through the said feed-tube.

In testimony whereof, I have signed my name to this specification, in presence of two subscribing witnesses.

ORVILLE VIRDEN.
